TOILET ROLL WINDER

Samuel J. Campbell, Green Bay, Wis.

Application September 2, 1948, Serial No. 47,372

4 Claims. (Cl. 242—55)

1

This invention relates to a parent roll drive applicable to any converting apparatus to provide web delivery at a predetermined lineal rate and from a predetermined point of delivery.

It is very common in machinery which delivers webs of paper or cloth or similar materials from a parent roll to effect delivery by means of feed rolls acting on the web and to apply some sort of a brake or drag to the parent roll which will act more or less continuously thereon. The parent roll is not ordinarily driven directly because to do so in any ordinary manner would involve a number of difficulties. For one thing, the lineal rate of delivery would vary according to the radius of the roll and for another thing, any attempt to act on the periphery of the roll would involve a tendency of the web to wrinkle, even to the extent of forming a loop at the point of contact. The present invention seeks to overcome the variation in radius by driving the periphery rather than the hub of the current roll and I have succeeded in overcoming the tendency to wrinkle by using a driving drum having a discontinuous peripheral surface.

These and other objects of the invention will appear more fully from the following disclosure thereof.

In the drawings:

Fig. 1 is a view diagrammatically illustrated of apparatus embodying the invention as viewed in section on the line 1—1 of Fig. 3.

Fig. 2 is a view taken in section on the line 2—2 of Fig. 1.

Fig. 3 is a view taken in section on the line 3—3 of Fig. 1.

While the invention is particularly described in connection with perforating apparatus for a toilet roll winder, it will be understood that this is merely by way of exemplification and that the invention has a wide range of utility wherever a web is to be unwound from a parent roll.

The frame of the converting apparatus comprises a pair of spaced side members 5 and 6 having bearings for the knife-equipped perforating roll 7 and the coacting feed roll 8. The latter is mounted upon the power input shaft 9 which carries pulley 10 driven by belts 11 from motor 12. The pulley 10 may include a pneumatically operated brake 13 which may be expanded by air admitted into the annular elastic tube 14 through pipe 15 subject to the control of an electromagnetic valve 16, this mechanism, however, forming no part of the present invention. The sheets may be counted and the apparatus controlled by an electrical switch 17 (Fig. 1 and

2

Fig. 2) operated by cam 18 driven through a gear seat 19 actuated by chain 20 from the power input shaft 9.

The present invention is more particularly concerned with the parent roll 25 and the means for delivering web 26 therefrom. For the purposes of the present exemplification, the web passes between the perforating roll 7 and the feed roll 8 as clearly shown in Fig. 1.

The parent roll is provided at the ends of the core 27 with plugs 28, 29 which are annular, being mounted by means of roller bearings 30, 31 upon inner races 32, 33. These races have flanged heads provided with set screws 34, 35 which fasten them to non-revolute shaft 36. This shaft is guided in the inclined slots 37, 38 which are open at their upper ends and closed at their lower ends as shown in Figs. 1 and 2. These slots may conveniently be formed in winglike extensions 39, 40 of the frame elements 5 and 6, the extensions being bolted in place as indicated in Figs. 1 and 2.

The non-revolute shaft 36 upon which the parent roll is mounted to turn may be adjusted to any desired axial position in order to shift the parent roll to one side of the machine frame or the other, so that the web will feed therefrom in the desired plane. For this purpose, the shaft 36 carries a flanged guide spool 42. Between the flanges of spool 42 is a bar 43 mounted on parallel links 44, 45 (Fig. 2 and Fig. 3), such links being pivoted to the frame wing extension 39 and to the bar. A nut 46 carried by the bar is in threaded engagement with an adjusting screw 47 at the end of shaft 48, the opposite end of the shaft being provided with a hand wheel 49 and positioned by stop collars 50, 51 at each side of a bracket 52 which projects from the frame member 5 and in which the shaft 48 is journaled. By rotating the hand wheel 49 to oscillate the guide bar 43 forwardly or backwardly, such bar is also caused to move inwardly and outwardly upon the respective links 44, 45 respecting the frame extension wing 39, thereby causing a corresponding reciprocation of the shaft 36 and parent roll 25 due to engagement of the guide spool 42 on such shaft with the bar 43.

The position of the parent roll and shaft 36 in the slots 37, 38 is determined by engagement of the periphery of the parent roll with a driving drum 55 substantially at the point where the web 26 leaves the periphery of the roll en route to the converting apparatus. The frame sides 5 and 6 are provided with suitable bearings 56,

57 for the shaft 59 upon which drum 55 is mounted. For driving the drum, I provide connections which desirably include change speed gearing. There is a pinion 60 on the main drive shaft 9 which meshes with a pinion 61 on a stud 62 projecting laterally from frame side 6. Below this, another stud at 64 adjustably carried on the crank 65, carries a change gear 66 which is merely an exemplification of any desired change speed mechanism for providing an accurately determinable rate of operation of the drum 55 with respect to the shaft 9 which operates the conversion mechanism, whatever that may be. A chain 68 connected with the hub of the change speed gear 66 operates over suitable sprockets to drive the shaft 59 upon which drum 55 is mounted.

An important feature of the invention consists in the construction of drum 55 to provide a discontinuous peripheral surface. This may conveniently be done by so constructing the drum that its periphery comprises angularly spaced axially extending slats 69. If the surface of this drum were continuous, the web of paper fed thereby from the parent roll 25 would form a wrinkle or loop. In the construction illustrated, the drum is actually free of the periphery of the parent roll, or substantially free thereof, momentarily every time one of the slats 69 passes from beneath the parent roll. The result is a feed which can be controlled with the greatest accuracy and which delivers the web smoothly and unwrinkled.

It will be obvious that the shaft 36 will move downwardly in the ways 37, 38 as the radius of the parent roll is reduced by the withdrawal of web 26 therefrom. At all times a portion of the weight of the parent roll will be borne directly by the frame extension wings 39, 40 and only a portion of such weight will be imposed on the driving drum 55, due to the inclination of the slots or weights in which the shaft 36 is disposed. While the shaft 36 does not revolve with the parent roll, it will rotate in frictional contact with the ways in the course of its downward movement thereon.

I claim:

1. A device of the character described comprising the combination with a feeding drum and inclined ways leading toward said drum, of a parent roll support comprising a shaft mounted on said ways and adapted to roll down said ways toward said drum, said shaft being adapted to be supported from said drum by a parent roll mounted on said shaft and contacting the drum, and means for controlling the axial position of said shaft in its movement down said ways, said position controlling means comprising a spool on said shaft, a guide bar paralleling said ways and engaged with said spool, and means for adjusting the position of said guide bar laterally respecting said ways.

2. A device of the character described comprising the combination with a feeding drum and inclined ways leading toward said drum, of a parent roll support comprising a shaft mounted on said ways and adapted to roll down said ways toward said drum, said shaft being adapted to be supported from said drum by a parent roll mounted on said shaft and contacting the drum, and means for controlling the axial position of said shaft in its movement down said ways, said position controlling means comprising a spool

on said shaft, a guide bar paralleling said ways and engaged with said spool, and means for adjusting the position of said guide bar laterally respecting said ways, the position adjusting means comprising links supporting the guide bar for maintaining it substantially parallel to the path of movement of said shaft in said ways, and a screw having a nut threaded thereon, the screw having means for its rotation and the nut having a connection with said guide bar for effecting movement thereof upon said links in a direction having a component axially of said shaft.

3. The combination with a support comprising inclined ways and a parent roll shaft mounted in said ways, and a second shaft having a converting machine connection, of a driving drum in operative driven connection with the second shaft and disposed in a position toward which said parent roll shaft rolls in said ways for engagement with a parent roll mounted on the shaft first mentioned for the delivery of a web therefrom at a lineal speed controlled by said drum, the periphery of the drum being discontinuous, in further combination with guide collars mounted on the parent roll shaft, a bar engaged with said collars and extending parallel to the movement of said shaft in said ways, and means for adjusting said bar laterally respecting the said direction of movement whereby to adjust the axial position of said shaft, and a parent roll carried thereby.

4. The combination with a support comprising inclined ways and a parent roll shaft mounted in said ways, and a second shaft having a converting machine connection, of a driving drum in operative driven connection with the second shaft and disposed in a position toward which said parent roll shaft rolls in said ways for engagement with a parent roll mounted on the shaft first mentioned for the delivery of a web therefrom at a lineal speed controlled by said drum, the periphery of the drum being discontinuous, in further combination with guide collars mounted on the parent roll shaft, a bar engaged with said collars and extending parallel to the movement of said shaft in said ways, and means for adjusting said bar laterally respecting the said direction of movement whereby to adjust the axial position of said shaft, and a parent roll carried thereby, the said guide bar being provided with spaced mounting links and an actuating nut, together with a screw provided with a hand wheel and meshing with said nut for effecting a longitudinal movement of said bar having a lateral component in the oscillation of said links.
